Patented Oct. 26, 1976

242,050

COMBINATION RADIO AND CASSETTE RECORDER

Tomoji Okada, Tokyo, Japan, assignor to General Electric Company, Syracuse, N.Y.

Filed May 30, 1975, Ser. No. 582,394

Term of patent 14 years

Int. Cl. D14—01

U.S. Cl. D26—14 B

FIG. 1

FIG. 2

FIG. 3

FIG. 4

FIG. 5

FIG. 6

FIG. 7

FIG. 1 is a front elevational view of a combination radio and cassette recorder showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a top plan view thereof with the carrying handle removed; and

FIG. 7 is a bottom plan view thereof.

I claim:

The ornamental design for a combination radio and cassette recorder, as shown and described.
